UNITED STATES PATENT OFFICE

MAGGY BESANCON DE WAGNER, OF PARIS, FRANCE, ASSIGNOR TO LENTHERIC, INCORPORATED, OF NEW YORK, N. Y., A CORPORATION OF NEW YORK

DESIGN FOR A BOTTLE

Application filed August 23, 1929. Serial No. 32,518. Term of patent 14 years.

To all whom it may concern:

Be it known that I, MAGGY BESANCON DE WAGNER, a citizen of France, residing in the city of Paris, France, have invented a new, original, and ornamental Design for Bottle, of which the following is a specification, reference being had to the accompanying drawing, forming a part thereof.

In the drawing,

Fig. 1 is a back view of my bottle.

Fig. 2 is a side view thereof.

Fig. 3 is a front view thereof.

I claim:

The ornamental design for a bottle substantially as shown.

MAGGY BESANCON DE WAGNER.
